UNITED STATES PATENT OFFICE

159,168

SANTA CLAUS DOLL

Elsie R. SchAAF, San Diego, Calif.

Application December 22, 1947, Serial No. 143,275

Term of patent 14 years

(Cl. D34—4)

To all whom it may concern:

Be it known that I, Elsie R. SchAAF, a citizen of the United States of America, residing at San Diego, in the county of San Diego and State of California, have invented a new, original, and ornamental Design for Santa Claus Doll, of which the following is a specification, reference being had to the accompanying drawing, forming a part thereof:

Figure 1 is a front elevational view of a Santa Claus doll showing my new design and Figure 2 is a side elevational view of a Santa Claus doll shown in Fig. 1.

I claim:

The ornamental design for a Santa Claus doll, substantially as shown.

ELsie R. SCHAAF.
